US00D712033S

(12) **United States Design Patent**
Richard et al.

(10) **Patent No.:** **US D712,033 S**
(45) **Date of Patent:** **** Aug. 26, 2014**

(54) **SEAL ANCHOR FOR USE IN SURGICAL PROCEDURES**

(71) Applicant: **Covidien LP**, Mansfield, MA (US)

(72) Inventors: **Paul D. Richard**, Shelton, CT (US);
Russell Heinrich, Madison, CT (US)

(73) Assignee: **Covidien LP**, Mansfield, MA (US)

Primary Examiner — Wan Laymon

(57) **CLAIM**

The ornamental design for the seal anchor for use in surgical procedures, as shown and described.

DESCRIPTION

FIG. 1 is a top perspective view thereof;

FIG. 2 is a top plan view thereof;

FIG. 3 is a front elevational view thereof;

FIG. 4 is a right elevational view thereof;

FIG. 5 is a back elevational view thereof;

FIG. 6 is a left elevational view thereof;

FIG. 7 is a bottom plan view of thereof; and,

FIG. 8 is a bottom perspective view thereof.

The broken lines included throughout the figures are for illustrative purposes and form no part of the claimed design.

1 Claim, 4 Drawing Sheets
